DONALD R. BATTLES, OF NEW LONDON, CONNECTICUT, ASSIGNOR TO ELECTRIC BOAT COMPANY, OF NEW YORK, N. Y., A CORPORATION OF NEW JERSEY.

TORPEDO-LAUNCHING APPARATUS.

1,184,409.

Specification of Letters Patent.

Patented May 23, 1916.

Application filed February 24, 1916. Serial No. 80,135.

To all whom it may concern:

Be it known that I, DONALD R. BATTLES, a citizen of the United States, and a resident of New London, in the county of New London and State of Connecticut, have invented certain new and useful Improvements in Torpedo-Launching Apparatus; and I do hereby declare the following to be a full, clear, and exact description of the invention, such as will enable others skilled in the art to which it appertains to make and use the same.

In launching an automobile torpedo under water from a boat moving at an angle to the direction in which the torpedo tube is trained, the water current tends to cause the torpedo to bind in the tube as it issues therefrom. Therefore, in submerged torpedo tubes adapted for broadside discharge from a warship or from the deck of a submarine boat, the practice heretofore followed involves mounting the tube on a pivot about which the tube may turn with the water current as the torpedo issues, thus relieving the binding tendency above referred to. Also, this pivot is arranged centrally of the tube so that the water pressure on the portions of the tube on opposite sides of the axis of the pivot is substantially balanced and produces no effective turning moment until the torpedo starts to issue in being discharged. A training mechanism is provided for turning the tube about its pivot, but it is preferable to have this training mechanism so arranged that the free turning movement of the tube, while the torpedo is being discharged therefrom, does not turn the training mechanism. Such a construction permits of the use of worm gearing in the training mechanism whereby the ratio of reduction desirable for hand operation is secured. It has therefore been proposed to provide a slip clutch between the tube and the training mechanism, and the friction between the clutch members is so adjusted that the turning effort to which the tube is subjected by the training mechanism is not sufficient to produce slipping, whereas the turning effort due to the unbalanced water pressure on opposite sides of the pivotal axis of the tube during dis-

charge of the torpedo is sufficient to effect a slipping movement of the clutch members when one of those members is locked against rotation by the worm gearing.

55

The present invention relates to an organization of this character and involves the provision of automatic means for actuating the clutch members whereby they will be held in engagement to prevent relative movement thereof while the tube is being trained but will be automatically disengaged when the firing mechanism of the tube is actuated, so that when the torpedo is issuing from the tube, the latter will be 65 free to turn under the influence of the unbalanced water pressure. The automatic release of the clutch is preferably effected directly by the firing mechanism; for instance, when compressed air is employed for 70 effecting the discharge of the torpedo from the tube, the admission of the compressed air to the tube may also be made to effect an automatic release of the clutch; or, if desired, the release of the clutch may be 75 effected electrically or in any other suitable manner, it being essential only that the release be effected automatically and as an incident of the firing of the torpedo so that the training mechanism will be positively 80 connected to the tube until the torpedo is fired but will be disengaged therefrom so as to allow the tube to turn freely when the torpedo is issuing from the tube.

The preferred embodiment of the invention, involving the use of pneumatic means for effecting the release of the clutch, is illustrated in the accompanying drawings, in which—

Figure 1 is an elevation, partly in section, 90 showing the central portion of the torpedo and the training mechanism therefor; Fig. 2 is an enlarged view of the friction clutch and the air valve therefor; and Fig. 3 is a bottom view of the trunk pivot of the tor- 95pedo tube and the piping connections thereon.

The torpedo tube 1, adapted to discharge an automobile torpedo of the well known kind, is arranged on the deck 2 of a submarine boat and is mounted on a turntable 3 supported on rollers 4 arranged on a cir-

cular track 5. The trunk pivot 6 forms a part of the turntable 3 and depends centrally therefrom. This pivot is located substantially midway between the ends of the 5 torpedo-tube, and thus when the boat is under way and the tube is submerged, the pressure of the water equalizes on the two ends of the tube so that there is no unbalanced moment sufficient to turn the tube 10 from any position of rest until such time as the torpedo during discharge starts to issue from the tube.

The trunk pivot passes through the water-tight bearing 7 into the interior of the 15 boat and is associated therein with suitable training mechanism, which may be operated by hand or otherwise and which is adapted to turn the tube to aim the torpedo at any desired mark. The training mechanism 20 illustrated includes a worm-wheel 8 fast to a shaped ring 9, and a worm 10 engaging with the worm-wheel and provided with a training handle 11.

The shaped ring 9 loosely embraces the 25 trunk pivot 6 and forms one member of a friction clutch interposed between the training mechanism and the torpedo tube. A complementary shaped ring 12 embraces the trunk pivot and is arranged to move axially 30 along the exterior of the latter but is keyed thereto so that the ring 12 and the trunk-pivot turn together in all positions of ring 12 axially of the trunk-pivot. A tubular annulus 13, preferably of rubber and of 35 rectangular cross-section as shown best in Fig. 2, forms a pneumatic, expandible operating device for actuating the friction clutch. This annulus 13 is received in and sustained in position by a supporting channel 14 mounted on the pivot 6 below rings 9 and 12. The arrangement of these parts 40 is such that when the tube is moved in azimuth by the training mechanism, the expandible annulus 13 is inflated and the ring 45 13 thereby raised so that the beveled surfaces of the two clutch members 9 and 12 are locked in engagement against slipping of one relatively of the other; and immediately on launching the torpedo, the expandible annulus 13 is connected to the atmosphere 50 so that it becomes deflated and ring 12 moves downward away from ring 9 an amount sufficient to permit ring 12 and the pivot 6 to turn independently of ring 9 and 55 the training mechanism without undue friction. Thus I interpose between the training mechanism and the tube what I term a "positively releasable clutch", such that the training mechanism is effective to turn the 60 tube without slipping at the clutch members prior to the discharge of a torpedo, and the unbalanced water pressure during torpedo-discharge is effective to turn the tube without turning the training mechanism because

of the slipping of the clutch members. This 65 change in the operation of the clutch members is effected automatically and simultaneously with the discharge of the torpedo. Preferably, the two operations are directly 70 associated so that the release of the clutch occurs as a direct result of operation of the 75 torpedo-launching mechanism.

In the construction shown on the drawings a suitable source of supply of compressed air under "low" pressure, say 100 80 lbs., is connected to pipes 26 and 27, said source being normally out of communication with the pipe 27 due to the presence and normal set of the firing-valve 28 (and due also in some cases to certain other valves not 85 here necessary to mention). The pipe 27 communicates through pipes 36, 31 and 29 with valve devices mounted within two 90 housings 25^a and 25^b, and when the firing-valve 28 is opened to admit compressed air 95 to pipe 27, the valve devices in the housings 25^a and 25^b are actuated to open the passage through a conduit 15 by which air under "high" pressure, say 200 lbs., is carried to a pipe 24 leading to the torpedo tube. Conduit 15 is connected directly to the high pressure air-line of the boat so that the instant firing-valve 28 is opened to actuate the valve devices whereby pipe 15 is controlled, the high pressure air flows through pipes 15 and 24 to the torpedo tube.

The means employed for opening the conduit 15 for the flow of compressed air to the torpedo tube are made to control the operation of the clutch consisting of the members 100 9 and 12. A valve-housing 33 (Fig. 2) is supported by and depends from the lower 105 face of the pivot 6. A pipe 19 leads from conduit 15 and opens into passages 20 formed in a cylinder 22 set within the 110 housing 23. Cylinder 22 has a piston-valve 16 mounted therein and undercupped to receive one end of a coiled spring 17, the other end of which takes about a stem on a cap 34. The cylinder 22 is also provided with passages 21 and 23. Passages 21 open into a pipe 18 communicating with the interior of the annulus 13. Passages 23 communicate with the atmosphere by way of 115 ports 37. The strength of spring 17 is such that normally it maintains the piston-valve 16 in the position illustrated. In this position, the air admitted to pipe 19 from conduit 15 flows through passages 20 and 21 and pipe 18 to the annulus and maintains 120 the annulus inflated so that training-handle 11 controls the rotation of the pivot 6. The piston-valve 16 is depressed against the tension of spring 17 when air enters the upper portion of housing 33 through a pipe 36 125 which communicates through a pipe 35 with the pipe 29 to which compressed air is admitted when the firing-valve 28 is opened.

The pressure of the air admitted through pipe 19 upon the piston-valve 16 balances that valve so that the compressed air admitted through pipe 36 forces the piston-valve 5 downwardly against the tension of spring 17. When the piston-valve 16 is so depressed the upper piston-valve closes passages 20 and the lower piston, uncovering the passages 23, places the pipe 18 in communication with the atmosphere; thus opening the firing-valve to effect the discharge of a torpedo from the tube operates the piston-valve 16 so as to permit the air in the annulus 13 to be exhausted to the atmosphere through pipe 18 and ports 21 and 23, and the annulus 13 becomes contracted and permits the clutch member 12 to move downwardly and out of hard engagement with the clutch member 9. It will thus be seen 20 that normally the clutch members 9 and 12 are held in engagement so that the tube may be turned about its pivotal axis by manipulation of the training mechanism but the operation of discharging the torpedo from 25 the tube effected by opening the firing-valve causes an automatic release of the clutch by which the training mechanism is connected to the pivot of the torpedo tube so that while the torpedo is issuing from the tube the 30 clutch members are out of engagement and the tube may be turned on its pivot by the unbalanced water pressure on the tube.

Having thus described my invention, what I claim is:

35 1. The combination with a pivoted torpedo tube, and training mechanism for turning the tube on its pivot, of a positively releasable clutch interposed between the tube and the training mechanism.

40 2. The combination with a pivoted torpedo tube, and training mechanism for turning the tube on its pivot, of a pressure-controlled positively releasable friction clutch interposed between the tube and the training 45 mechanism.

3. The combination with a pivoted torpedo tube, and training mechanism for turning the tube on its pivot, of a friction clutch interposed between the tube and the training 50 mechanism, and an expansible device effective upon expansion to hold the clutch members in engagement and effective upon contraction to release the clutch members for free slipping movements.

55 4. The combination with a pivoted torpedo tube, and worm gearing for turning the tube on its pivot, of a positively releasable clutch interposed between the tube and the worm gearing.

60 5. The combination with a pivoted torpedo tube adapted to contain a torpedo, training mechanism for turning the tube on its pivot, and firing mechanism for discharging the torpedo from the tube, of mechanism

which is associated with the firing mechanism and which positively releases the training mechanism from the tube when the firing mechanism is actuated to discharge the torpedo.

6. The combination of a pivoted torpedo 70 tube, training mechanism for turning the tube on its pivot and means for automatically disconnecting the training mechanism from the tube when a torpedo is discharged from the tube.

7. The combination of a pivoted torpedo tube, training mechanism for turning the tube on its pivot, a clutch mechanism for connecting the training mechanism to the pivot of the tube and means for actuating 80 the clutch mechanism to release the tube from the training mechanism when a torpedo is discharged from the tube.

8. The combination of a pivoted torpedo tube having a depending pivot, training 85 mechanism for turning the torpedo tube including a gear loosely mounted on the depending pivot, a friction member coöperating with said gear and fastened on the pivot, and means for holding the friction member 90 and gear in engagement to connect the latter with the pivot of the tube, and for releasing the friction member from engagement with the gear to permit free relative movement thereof.

9. The combination of a pivoted torpedo tube, training mechanism for turning the tube on its pivot, an air-controlled friction clutch interposed between the tube and the training mechanism, and an air-valve rendering the air effective and ineffective on the clutch.

10. The combination of a pivoted torpedo tube adapted to contain a torpedo, training mechanism for turning the tube on its pivot, 105 firing mechanism for discharging the torpedo from the tube, a friction clutch interposed between the tube and the training mechanism, an expansible device effective upon expansion to hold the clutch members 110 in engagement against slipping and effective upon contraction to release the clutch members for free slipping movement, and an air-valve coöperating with the firing mechanism to release the clutch when the firing mechanism is actuated to discharge the torpedo.

11. The combination of a pivoted torpedo tube, training mechanism for turning the tube on its pivot, a first air-line normally open, a second air-line normally closed but 120 adapted when open to fire a torpedo from the tube, a friction clutch interposed between the tube and the training mechanism, an expansible device effective upon expansion to hold the clutch members in engagement and 125 upon contraction to release the clutch members for free slipping movement, a valve casing having a first port in communication

with the first air-line and a second port in communication with the interior of said expansible device and having also a third port in communication with the second air-line and a fourth port in communication with the atmosphere, a valve in said casing normally uncovering the first and second ports and

covering the fourth port, and means for opening the second air-line so that air will be fed therefrom through the third port to 10 cause the valve to close said first port and open said fourth port.

In testimony whereof I affix my signature.

DONALD R. BATTLES.
